UNITED STATES PATENT OFFICE.

SERGIUS STEINBERG AND IGOR GRAMOLIN, OF MOTOWILICHI, RUSSIA.

ELECTRODE-HOLDER FOR ELECTRIC FURNACES.

1,280,576.

Specification of Letters Patent.

Patented Oct. 1, 1918.

Application filed July 19, 1916. Serial No. 110,094.

To all whom it may concern.

Be it known that we, SERGIUS STEINBERG and IGOR GRAMOLIN, subjects of the Czar of Russia, residing at Motowilichi, Government of Perm, Russia, have invented certain new and useful Improvements in Electrode-Holders for Electric Furnaces, of which the following is a specification.

This invention relates to electric furnaces of the resistance type for the purpose of melting steel. In the form of furnace which will be now described, the furnace chamber is similar to that of the common Martin furnace. One or more of its vertical sides are provided with openings through which material may be charged into the furnace or through which the necessary metallurgical treatment may be performed, the openings being furnished as usual with closing doors. One of the sides is provided, as usual, with an opening to permit of the discharge of the melted steel, such opening being adapted to be closed by any suitable means.

The furnace chamber is constructed of a carbon or graphite mass, is absolutely non-fusible and is adapted to absorb any traces of atmospheric oxygen entering into the furnace, and thus preventing the carbon electrodes from being consumed. The furnace is shown as of the rocking type, but it may be also made stationary as a fixture.

In the accompanying drawings Figure 1 shows the rocking furnace in side sectional view while Fig. 2 is a transverse sectional view thereof.

The heat energy required for smelting and for the necessary metallurgical processes is obtained from carbon electrodes *a* which are arranged across the furnace chamber and directly underneath the furnace vault, and heated by the electric current which is passed through them.

The current may be direct, alternating or three-phase, and the size of the electrodes and the distribution of the current will depend upon the size of the furnace and the nature of the electric current employed.

Each electrode *a* is clamped between two copper or graphite shoes *b* of special shape forming contact blocks which are screwed on to the copper bushes *c* which are arranged within suitable openings in the furnace walls, and are cooled by water circulation which is adapted to be passed through the hollow space formed therein. The bushes *c* are loosely arranged and mounted in the sides of the furnace within special openings and are pressed against the ends of the electrode *a* by screws *e* and through the medium of springs *d*. Instead of spring compression a dead load compression, such as a weight may also be employed. In this way constant contact between the electrode *a* and the copper or graphite shoes *b* is insured independently of the tension and compression due to the heating and cooling of the electrodes *a* as well as the furnace chamber. The cooling water is led into the bushes or sleeves *c* through the rubber and copper pipes *f*.

Having now described my invention, what I claim as new and desire to secure by Letters Patent is:—

Electrode holder for electric furnaces for the continuous treatment of steel, comprising a furnace chamber in combination with carbon electrodes extending across the chamber, block contacts abutting against each end of each electrode and situated in the chamber walls, hollow movable metallic sleeves for holding the block contacts, water circulation within the sleeves and spring and screw devices for pressing the sleeve upon the block contacts and thus causing the latter to press upon and support the electrodes.

In testimony whereof we affix our signatures in presence of two witnesses.

SERGIUS STEINBERG.
IGOR GRAMOLIN.
